LIGHTING FIXTURE

Louis Gilman, Boston, Mass.

Application September 30, 1947, Serial No. 141,659

Term of patent 14 years

(Cl. D48—23)

To all whom it may concern:

Be it known that I, Louis Gilman, a citizen of the United States, residing in Boston, in the county of Suffolk and State of Massachusetts, have invented a new, original, and ornamental Design for a Lighting Fixture, of which the following is a specification, reference being had to the accompanying drawing, forming a part thereof, in which the single drawing figure is a bottom perspective view of a lighting fixture, showing my new design. The opposite side and end are the same respectively as those shown.

I claim:

The ornamental design for a lighting fixture, as shown and described.

LOUIS GILMAN.
